UNITED STATES PATENT OFFICE

JOHN H. SCHREIBER, OF ST. LOUIS, MISSOURI

ICE SCORING MACHINE

Application filed February 7, 1929. Serial No. 338,107.

This invention relates to an ice scoring machine for scoring diametrically opposite sides of an ice block by a single set of scoring devices with which said opposite sides of the ice block are successively brought into contact.

Objects of the invention are to provide a machine of the type and character mentioned which may be made and sold at comparatively low cost and which include a minimum number of working parts assembled into a compact machine to occupy a comparatively small amount of floor space; to provide the machine with means for catching and removing the snow produced by operation of the machine on the ice blocks; to provide means for preventing operation of the machine when no ice block is in position for scoring; to provide means for automatically enclosing the scoring devices so as to render the machine safe when it is not in use; and to provide a single set of scoring devices for scoring on more than one side of the ice block.

Numerous other objects and the advantages of my improved machine will appear from the following description, reference being made to the accompanying drawings in which

Fig. 1 is a plan view of my improved machine.

Fig. 2 is a side elevation.

Fig. 3 is a top plan view of the machine with the top plate removed.

Fig. 4 is a front elevation of the machine.

Fig. 5 is a cross sectional view of the machine approximately on the line 5—5 of Fig. 2 with an ice block therein which has been scored on one side and which is being scored on another side.

Fig. 6 is a vertical sectional view approximately on the line 6—6 of Fig. 1.

In the embodiment of the invention shown my improved machine comprises a base 1 having an outlet 2 for discharging into a drain pipe 3 the snow produced by operation of the scoring devices on the ice blocks. Two upright angle bars 4 are rigidly secured to opposite sides of the base and each has on its lower end a curved extension 5 (Fig. 2). The extensions 5 curve around the edge of the base

to abutting contact with an upright channel bar 6. The channel bar 6 is secured in upright position by rigid supporting elements 7 (Fig. 6) and the angle bars 4 are secured in upright position by attachment to projections 8 forming rigid guide chutes 9. These guide chutes 9 are connected by an outwardly curved strap or bar 10 and by an inwardly curved strap or bar 11. The chutes 9 are therefore rigid with each other and rigid with the frame of the machine comprising the base 1 and the bars 4. The upper ends of the bars 4 are connected by an angle bar 12 having a notch 13^a.

The top plate 13 of the machine is rigidly attached to the upper ends of the bars 4 and 6 and to the bar 12 and projects forwardly beyond the bars 4. An electric motor 14 is removably attached to the top plate 13 by removable fasteners 15 and is controlled by a switch 16 mounted on the top plate 13 in convenient position for operation by the person in charge of the machine. The motor shaft 17 is connected to the upper end of a vertical shaft 18 by an insulation coupling 19. The lower end of the shaft 18 is mounted in a bearing 20 supported by the bar 11. The shaft 18 supports a series of scoring devices comprising circular saws 21 mounted on the shaft in spaced relationship and projecting forwardly beyond the plane of the bar 11.

A turntable 22 operates upon a bearing 23 on the forward extension of the base 1 and has along its outer edge a flange 24 and along its inner edge a guide flange 25. An upright channel bar 26 has its lower end attached to the turntable 22 and supports a number of spaced supporting arms 27 against which the blocks of ice are held when the machine is operating. The upper end of the bar 26 supports a bracket 28 to which is rigidly secured an internal gear 29. The gear 29 has an axle 30 journaled in a bearing 31^b attached to the top plate 13. The axle 30 is in axial alignment with the bearing 23 so that the frame comprising these parts is rotative. An ice block holder comprising a bail 31 has its ends pivoted to the bracket 28 and is movable to and from position to embrace the upper end of an ice block mounted on the turntable 22 as will be readily understood by reference to Fig. 6.

An angular latch spring 32 is attached to the front end of the bail 31 and is movable into and out of latching engagement with the top plate 13, said plate being formed with a notch 33 in its forward edge to receive said latch spring. When the latch spring 32 is in latching engagement with the top plate 13 the bail 31 is supported thereby in the position indicated by broken lines in Fig. 6 so as to permit movement of an ice block onto or from the turntable 22. A handle 34 is attached to the front end of the bail 31 for manipulating the same.

A hand wheel 35 is attached to the upper end of a shaft 36 journaled for rotation in a bearing 37 rigid on the top plate 13. The lower end of the shaft 36 has rigid thereon a pinion 38 meshing with the internal gear 29 so that said gear 29 and thereby the turntable 22 may be rotated by said wheel 35.

The side flanges 24 and 25 of the turntable 22 are arranged so that when the machine is idle said flanges are in alinement with the chutes 9 to permit movement of an ice block through either of said chutes onto the turntable and subsequent removal of the scored ice block from the machine. The turntable is normally held in this position by a lever 39 mounted on a pivot 40 in connection with the top plate 13 and having a tooth 41 designed and arranged to engage in a notch in the periphery of the internal gear 29 (Fig. 3). The lever 39 is actuated to this latching engagement by a longitudinally movable stem 42 having one end abutting against an arm 43 on said lever 39 and the opposite end in connection with a slideable valve device 44 in a water pipe 45. A spring 46 is mounted on the stem 42 having one end abutting against the valve support 44 and the opposite end against a collar 47 on said stem. Thus the spring 46 is utilized to actuate the lever 39 to an extent to latch said lever with the gear wheel 29 and is also utilized to move the valve stem 42 in a direction and to an extent to close the valve in the pipe 45. Thus when the turntable is latched in starting position the valve 44 is closed. And when the machine is in use and the turntable is being rotated the lever 39 is held in position in which the valve 44 is open so as to permit discharge of water through a nozzle 48 in order to wash the snow through the outlet 2 into the drain pipe 3.

A casing is provided for the machine, the same comprising walls 49 each having one vertical edge hinged to the bar 6 by hinges 50 (Fig. 3) and the other edge provided with a pivoted latch element 51 movable into and out of engagement with a keeper 52 on the adjacent bar 4. These walls 49 are, therefore, capable of being swung from and to closed positions and when open afford access to the inside of the machine. When closed 65 the walls 49 confine the snow so that the snow

will be forced down to and through the outlet 2 and the drain pipe 3.

When the machine is to be used the turntable 22 is adjusted so that a block of ice may pass thereto from either of the chutes 9. The block of ice is then moved onto the turntable and the bail 31 is lowered from the broken line position to the solid line position, as shown in Fig. 6, so as to hold the block of ice against the supporting arms 27. The motor being started, the scoring saws 21 are rapidly rotated. The latch lever 39 is then released from latching engagement with the gear wheel 29 which opens the valve 44 and causes a flow of water through the nozzle 48 sufficient to wash the snow through the outlet 2 into the drain pipe 3. The hand wheel 35 is then rotated which rotates the support or frame on which the block of ice is mounted, bringing opposite edges of the block of ice successively into contact with the scorers 21 so that parallel kerfs or scores are formed in opposite sides of the block of ice, as will be understood by reference to Fig. 5. The rotative frame on which the ice is mounted is stopped in its initial or starting position automatically because when the notch in the wheel 29 is brought opposite the tooth 41 the spring 46 acts to move the lever 39 in a direction and to an extent to engage the tooth 41 in the notch in said wheel 29. Then the bail 31 is raised to latching engagement with the top plate 13 so as to permit the scored block of ice to be moved from the machine. The rotative ice block supporting frame cannot be latched in any other than its proper position to receive a block of ice.

If the spring 33 of the bail 31 becomes unlatched or disconnected from the plate 13 when there is no block of ice on the turntable 22 one or both of the extreme inner ends 31^a of the bail 31 will engage in the notch or notches 13^a and thus positively prevent the turntable 22 from being turned by the wheel 35 or otherwise. Accordingly, this arrangement acts as a safety device to prevent operation of the turntable when the machine is empty.

From the foregoing it is apparent that my invention obtains all of its intended objects and purposes in a highly satisfactory and efficient manner; that the operative mechanism is covered and enclosed in order to prevent accidents; that the snow produced by the scoring devices is trapped by the machine and is flushed from the machine automatically and as an incident to the operation of the machine; that the rotary ice block supporting frame is stopped automatically in position to receive and to discharge the blocks of ice; that the machine is compact and may be mounted in a comparatively small space; that the machine includes a minimum number of parts and may be manufactured and sold at low cost; and possesses many other advan-

tages made apparent by the foregoing description.

I do not restrict myself in unessential particulars, but what I claim and desire to secure 5 by Letters Patent is:—

1. An ice scoring machine comprising scoring devices, mechanism for operating said scoring devices to score blocks of ice brought into contact with said device, and mechanism 10 for supporting and rotating a block of ice about its vertical axis to bring more than one side of the block of ice into contact with said scoring devices whereby the same scoring devices will form scores in more than one 15 side of the block of ice.

2. A machine of the character described comprising scoring devices, mechanism for operating said scoring devices, and mechanism 20 for supporting and rotating an ice block about a vertical axis to bring a number of sides of the ice block successively into contact with the scoring devices.

3. A machine of the character described comprising a scoring element, mechanism for operating said scoring element, a rotary support for a block of ice, and mechanism for 25 rotating said support about a vertical axis to turn different sides of the block of ice successively into contact with said scoring device.

4. A machine of the character described comprising scoring means, mechanism for operating said scoring means, and mechanism for supporting and moving a block of ice to 30 an extent to bring different vertical sides of the block of ice into contact with the scoring means while the axes of the scoring means and the ice block remain the same distance apart.

40 5. A machine of the character described comprising scoring means, mechanism for supporting and moving a block of ice in a direction and to an extent to bring opposite sides of the block of ice into contact with the same scoring means, and a device for holding the block of ice on said mechanism and preventing operation of said mechanism when said device is out of engagement with a block of ice on said mechanism.

45 6. A machine of the character described comprising a scoring element, mechanism for supporting and moving a block of ice to an extent to engage different sides of the block of ice with said scoring element, a device for engaging and holding a block of ice on said mechanism, and means cooperating with said device to prevent operation of said mechanism when said device is out of engagement with said block of ice on said mechanism.

50 65 7. A machine of the character described comprising a vertical series of scoring devices, mechanism for supporting and rotating a block of ice about its vertical axis to an extent to bring different sides of the block of ice into contact with said scoring devices,

guards for said scoring devices supported by said mechanism, and means for preventing operation of said mechanism when no block of ice is on said mechanism.

8. A machine of the character described 70 comprising scoring means, a rotative support for supporting and rotating a block of ice about its vertical axis and into contact with said scoring means, and mechanism for operating said support.

75 9. A machine of the character described comprising scoring means, a rotative support for supporting and moving a block of ice into contact with said scoring means, mechanism for operating said support, and means for holding a block of ice on said support and for preventing operation of said support when no block of ice is on said support.

10. A machine of the character described 85 comprising a scoring element, a rotary support for supporting and moving a block of ice into contact with said scoring element, a bail for holding the block of ice on said support, and means cooperating with said bail to prevent said support from turning when said bail is out of contact with a block of ice on said support.

90 11. A machine of the character described comprising a vertical shaft, scoring members attached to said shaft, mechanism for rotating said shaft, and a device for supporting and rotating a block of ice about a vertical axis to bring different sides of the block of ice into contact with said scoring members.

95 12. A machine of the character described 100 comprising scoring means, a device supported for rotation about a vertical axis for supporting and rotating a block of ice into contact with said scoring means, mechanism for operating said scoring means, and other mechanism for rotating said device.

105 13. A machine of the character described comprising scoring means, a device supported for rotation about a vertical axis for supporting and rotating a block of ice into contact with said scoring means, mechanism for operating said scoring means, other mechanism for rotating said device, and means controlled by said device for guarding said scoring means.

110 14. A machine of the character described comprising scoring saws, mechanism for operating said saws, a device supported for rotation about a vertical axis for supporting and rotating an ice block into contact with said saws, means forming passages for guiding ice blocks onto and from said device, and mechanism for rotating said device.

115 15. A machine of the character described 125 comprising scoring saws, mechanism for operating said saws, a device supported for rotation about a vertical axis for supporting and rotating an ice block into contact with said saws, means forming passages for guiding ice blocks onto and from said device, mechanism 130

for rotating said device, and means supported by said device and operated thereby to position to guard the saws when said device is in position to receive or discharge an ice block.

16. A machine of the character described comprising scoring means, mechanism for supporting a block of ice in position for operation of the scoring means to form scores in said block, a device for holding said mechanism in a starting position, and means controlled by said device for removing the snow from the machine during operation of said mechanism.

17. A machine of the character described comprising scoring mechanism, a support for supporting and moving a block of ice into contact with the scoring mechanism and causing the scoring mechanism to form scores in the block of ice and to discharge the snow from the block of ice, a device for holding said support in a starting position, and means controlled by said device for removing the snow from the machine when said device is out of starting position.
